CLOTHES HAMPER

Wesley F. Junker, Copiague, and Alan A. Hicks,
New York, N. Y.

Application March 26, 1957, Serial No. 45,448

Term of patent 14 years

(Cl. D58—4)

Fig. 1 is a top plan view of a clothes hamper showing our new design.

Fig. 2 is a perspective view of the clothes hamper of Fig. 1.

The side not shown is the same as the side shown.

The characteristic features of our design for the clothes hamper disclosed reside in the cover and handle portions having the configurations shown.

We claim:

The ornamental design for a clothes hamper, as shown and described.
